UNITED STATES PATENT OFFICE.

CHESTER ROWELL SUTTON, OF TUCSON, ARIZONA, ASSIGNOR TO PERFECTION COOLING AND VENTILATING COMPANY, OF TUCSON, ARIZONA, A CORPORATION OF ARIZONA.

COOLING SYSTEM.

1,301,794.

Specification of Letters Patent. Patented Apr. 22, 1919.

Application filed November 19, 1917. Serial No. 202,705.

To all whom it may concern:

Be it known that I, CHESTER R. SUTTON, a citizen of the United States, residing at Tucson, in the county of Pima, State of Arizona, have invented certain new and useful Improvements in Cooling Systems, of which the following is a specification.

My invention relates to various features of novelty and improvement in cooling systems, and more particularly, but not restrictedly, pertains to advantageous structural features in what may be termed an "iceless refrigerator" system, employing the well-known principle of the rapid evaporation or vaporization of a liquid, such as water, to produce the cooling effect. The improved system is equally available for use in maintaining rooms or houses at a reduced temperature.

The prime object or leading feature of the present invention is the production of an appliance or system of this character which is simple in structure, economical to produce, and effective in the obtaining of results.

The invention resides in the mechanical construction of the various parts and their association and co-operation with one another, producing by their combined action the required function in a better, simpler, and more complete and effective manner than has heretofore been possible.

In the preferred embodiment of the invention, means are employed for humidifying or moistening the air which is delivered to the room, house, or compartment containing the iceless refrigerator, and means are also used for causing an adequate circulation of the air to accomplish the evaporation of the moisture sufficiently rapidly to produce the desired cooling effect.

In the particular embodiment of the invention presented in this application, a water-driven air-fan, either wholly or in part, creates the desired air flow and the water used for driving or rotating the fan is also employed for moistening or humidifying the air and reducing its temperature. The action of this fan may be supplemented or augmented so far as the production of a draft or air current is concerned, and the necessary vaporization assisted, by means of a heating appliance which performs this double useful function of facilitating and aiding the travel of the air and augmenting

or hastening the required evaporation of the moisture.

In order that a full and complete understanding of the invention and its various benefits and advantages may be had, I have illustrated a preferred and desirable embodiment of the same in the accompanying drawings throughout the views of which like reference characters refer to the same parts.

Referring to the drawing:

Figure 1 illustrates in section, and more or less diagrammatically, the complete system or apparatus, and

Fig. 2 is an enlarged section on lines 2-2 of Fig. 1 showing the air-fan driven by water-power.

The appliance includes a compartment, 7, (such as a room, house, or other chamber), which may or may not house or contain an iceless-refrigerator 8, conveniently formed of a suitable framework covered with a textile fabric 9, such as cotton-cloth, the refrigerator being supplied, as is customary, with a plurality of reticulated or openwork shelves or ledges 10, adapted to support the articles to be maintained in cool condition. This compartment 7, by means of a conduit 11, is connected to a chamber 12 provided with a central air inlet or admission tube 13 or pipe 13 extending downwardly thereinto a substantial distance, as shown, and supported on brackets 14, 14. Such pipe or tube 13 and the chamber 12 contain a rotatably-mounted vertical shaft 15 carrying a horizontal duplex air-fan structure comprising inner blades or vanes 16 in the tube 13 and outer reversely-pitched or oppositely-inclined blades or vanes 17 located in the space between the tube 13 and the wall of the chamber. The outer portion of this fan is composed of a ring 18 carrying a series of buckets or fins 19 against which a jet of water delivered from a nozzle 20 plays so as to bring about a rapid rotation of the fan.

Such fan also comprises an inner ring 21 between the blades 16 and 17 forming a direct intermediate continuation of the tube 13 as shown in Fig. 1, being of practically the same diameter as that of the tube. The lower portion of the chamber 12 is provided with a drain 22, and, in addition, the two compartments 7 and 12 at their lower portions are connected by an inclined pipe 23, whereby any water tending to collect in the

2
lower portion of the compartment 7 will automatically flow into the chamber 12 and from such chamber be drawn off through the drain 22.

5 The upper portion of the compartment 7 by a tube or pipe 24 is connected to a heater 25 which in turn has a discharge pipe 26 for the air. Heater 25 is internally supplied with two headers 27 and 28 connected together by a plurality of tubes 29, somewhat like an ordinary tubular boiler, so that the air in the pipe 24 can readily pass through such tubes 29 to the discharge pipe 26. The heater comprises a gas or other burner 30, 10 the heated products of combustion from which through tube 31 to the space between the headers and from such compartment 32 they flow off at the top through the delivery pipe 33, the chamber 32, however, preferably 15 20 being equipped with a pair of baffle plates 34 and 35 necessarily causing an indirect or tortuous flow of the heated air from the burner through such chamber before it is delivered into the discharge pipe 33. It will 25 be readily understood, however, that the products of combustion from the burner 30 do not in any way come in contact with the air passing through the heater 25. Obviously, any other suitable style or type of 30 heater might be used with much the same advantage.

The operation of the apparatus occurs practically as follows:

35 The duplex fan or blower 16, 17, is rapidly rotated by means of the jet of water from the nozzle 20 directed against the vanes or fins 19. This causes the fan 16 to spin rapidly and to draw in air through the inlet pipe 13 and then such air, in passing up- 40 wardly between the tube 13 and the casing wall 12, is acted upon by the reverse fan 17, the two fans thus working in conjunction to deliver the air through the tube 11 into the compartment 7. It will be observed, 45 however, that the water employed in driving the fan is also used to moisten or humidify the air and also to cool it, such water in striking the vanes being sub-divided or spattered or sprayed so that the air passing 50 through the appliance becomes adequately charged with cool moisture and at the same time cooled. The surplus water, of course, drains off through the pipe 22 and any excess water in the compartment 7 likewise drains 55 off through the pipes 23 and 22.

If desired, the water may be permitted to accumulate in chamber 12 sufficiently so that tube 13 projects into it slightly, whereby fan 16 positively forces the blast of air 60 through the water which of course during this action would become charged with moisture.

This cool, moisture-laden air causes the required cooling effect in compartment 7 65 and on the refrigerator contents. In order

to augment or increase the flow of air, the passage or draft of the air is supplemented by the action of the heating appliance. That is to say, the heating of the air in the device 25 creates a draft or suction in the 70 tube 24 and compartment 7, thus increasing the air current flow and augmenting its cooling function.

While I have herein presented only one desirable embodiment of the invention, it 75 is to be understood that it is susceptible of a variety of embodiments, and that many minor mechanical changes may be made in the apparatus as presented without departure from the substance and essence of the 80 invention and without the sacrifice of any of its substantial benefits and advantages. For example, if desired, the heating appliance may be omitted, but for the most effective work under ordinary conditions it is 85 found to be advantageous. Instead of using a duplex or compound fan 16, 17, a fan or blower of different or simpler construction might be used, and instead of driving it by water power, it could be rotated by other 90 means and the moisture supplied in any convenient way. Stated somewhat otherwise, to those skilled in this art various suggestions for minor changes will present themselves, all of which are embraced within the 95 scope of the invention as defined by the appended claims.

The appliance as will be appreciated, comprises both an air washing and cooling system which may be used to advantage 100 either with or without the iceless refrigerator because, even with such refrigerator absent, the compartment 7 is cooled by the passage of the cool humidified air there- 105 through.

I claim:

1. In a cooling appliance of the character described, the combination of a humidifying chamber, a conduit in said chamber open to the outer atmosphere and spaced away 110 from its wall, a fan in said chamber, and means to drive said fan and supply moisture to the current of air, whereby the air traverses said conduit and the space between the walls of said conduit and said chamber 115 and becomes cooled and humidified, substantially as described.

2. In a cooling appliance of the character described, the combination of a humidifying chamber, a conduit in said chamber 120 open to the outer air and spaced away from its wall, a fan in said conduit, and means to drive said fan and supply moisture to the current of air between the walls of said conduit and chamber, whereby the air traverses 125 said conduit and the space between the walls of said conduit and chamber and becomes cooled and humidified, substantially as described.

3. In a cooling appliance of the character 130

described, the combination of a humidifying chamber, a conduit in said chamber open to the outer air and spaced away from its wall, a water-driven fan in said chamber, and means to direct water against and to drive said fan and humidify the current of air, whereby the air traverses said conduit and the space between the walls of said conduit and chamber and becomes cooled and 10 humidified, substantially as described.

4. In an appliance of the character described the combination of a humidifying chamber, a conduit in said chamber open to the outer air and spaced away from its wall, 15 a water-driven fan in said conduit, and means to conduct water between the walls of said conduit and chamber to rotate said fan and humidify and cool the air, whereby the air traversing said conduit and the space between the walls of said conduit and chamber becomes cooled and humidified, substantially as described.

5. In a cooling appliance of the character described, the combination of a humidifying chamber, a conduit in said chamber open to the outer air and spaced away from its wall, a duplex-fan having a portion in said conduit and a portion in the space between the walls of said conduit and chamber, said 25 portions being adapted to conjointly create a current of air, and means to rotate said fan and supply moisture to said current of air, whereby the air traversing said conduit and the space between the walls of said conduit and said chamber becomes cooled and humidified, substantially as described.

6. In a cooling appliance of the character described, the combination of a humidifying chamber, a conduit in said chamber open

to the outer air and spaced away from its 40 wall, a water-driven duplex-fan having a portion in said conduit and a portion in the space between the walls of said conduit and chamber, said portions being adapted to conjointly create a current of air, and means to 45 direct water against and to drive said fan and humidify the current of air, whereby the air traversing said conduit and the space between the walls of said conduit and chamber becomes cooled and humidified, substan- 50 tially as described.

7. In a cooling appliance of the character described, the combination of a humidifying chamber, a conduit in said chamber spaced away from the wall of the latter thereby providing an air passage through said conduit and the space between the walls of said conduit and chamber, a fan to create a current of air through said passage, and means to supply moisture to said current of air whereby to 55 cool the latter, substantially as described.

8. In a cooling appliance of the character described, the combination of a humidifying chamber, a conduit in said chamber spaced away from the wall of the latter, the 65 space in said conduit and that between the walls of said conduit and chamber providing an air passage, a fan to create a current of air through said passage, means to rotate said fan, and means to supply moisture to 70 one of said spaces, whereby the air comes into direct contact therewith in such space and is additionally cooled in the other space by the cooling effect of such moisture on the wall of the conduit, substantially as de- 75 scribed.

CHESTER ROWELL SUTTON.
